UNITED STATES PATENT OFFICE

104,717

DESIGN FOR A PLATE OR SIMILAR ARTICLE

Edgar Mott Bottome, Moundsville, W. Va., assignor to Fostoria Glass Company, Moundsville, W. Va., a corporation of West Virginia

Application April 10, 1937, Serial No. 68,666

Term of patent 3½ years

To all whom it may concern:

Be it known that I, Edgar Mott Bottome, a citizen of the United States of America and resident of Moundsville, county of Marshall, and State of West Virginia, have invented a new, original, and ornamental Design for a Plate or Similar Article, of which the following is a specification, reference being had to the accompanying drawing, forming part thereof, in which—

The single figure is a top plan view of a plate

or similar article, showing my new design. In said figure the outline of the plate is depicted by dotted lines.

The essential feature of the invention resides in the surface ornamentation borne by the plate.

I claim:

The ornamental design for a plate or similar article, substantially as shown and described.

EDGAR MOTT BOTTOME.
